UNITED STATES PATENT OFFICE.

CHARLES A. BREWER, OF NOROTON HEIGHTS, CONNECTICUT, ASSIGNOR TO CANNON ENGINEERING CO., OF BROOKLYN, NEW YORK, A CORPORATION OF NEW YORK.

SADIRON.

Application filed January 29, 1926. Serial No. 84,613.

This invention relates, generally, to improvements in sad irons provided with means for dampening the goods undergoing pressing operations.

5 This invention has for its principal object to provide in combination with a sad iron body, means to furnish a supply of water within the iron body, together with a controllable means for spraying water from 10 said supply upon the goods in advance of the iron as the latter is moved over the goods to press the same.

Other objects of this invention, not at this time more particularly enumerated, will be 15 clearly understood from the following detailed description of the same.

The invention is illustrated in the accompanying drawing, which shows in part a side elevation and in part a sectional view 20 of the iron.

Referring now to said drawing, the reference character 1 indicates the body portion of the iron, which is suitably formed to provide a hollow interior 2. Arranged in connection with the lower part of said hollow interior is a suitable heating means, preferably in the form of an electrical heating unit (not shown) adapted to cooperate with the pressing face portion 3 of the iron body. 25 30 Suitably attached to the upper side of said iron body 1, by bail members 4, is a hand grip member 5 by means of which the iron may be grasped and manipulated.

The reference character 6 indicates an air pipe which is provided with a suitable control valve. The forward or discharge end of said air pipe is extended downwardly to the toe of the iron, and connected with said discharge end is an air jet member 7, the free 35 40 45 end of which is exteriorly disposed at the toe of the iron. Said air pipe 6 may be supported in connection with the iron structure in any manner and by any means found desirable and convenient, but preferably is mounted in connection with and supported by said hand grip member 5 by extending the same rearwardly and longitudinally therethrough, as shown in the drawing. Connected with the rear end of said air pipe 6, 50 55 60 by being threaded thereto or in any other convenient manner, is a cut-off valve casing 8, having an intake port 9 which extends through the neck or rearward extension 10 thereof. Suitably coupled in connection with 65 said neck or rearward extension 10 is a flex-

ible air hose 11 leading from any suitable source of air under pressure. Rotatably mounted in said valve casing 8 is a valve member 12 having a valve port 13 normally turned out of alignment intermediate the intake port 9 and the bore of said air pipe 6. Secured to the external end of said valve member 12 is an actuating lever 14 normally positioned in upwardly swung relation to the hand grip member 5 as determined by a stop 60 projection 15 on the valve casing, in which disposition the valve member is turned to air cut-off or closed position. A spring means, as 16, may be utilized in connection with said lever 14 to hold the latter in normal valve 65 closing position.

Secured within the upper portion of the hollow interior 2 of said iron body is a suitable water reservoir 17. Associated with said water reservoir is a water discharge 70 siphon 18, the rising leg 19 of which rises upwardly from the lower interior of said reservoir, and the descending leg 20 of which projects exteriorly and is carried downwardly and forwardly so that its free or discharge end 21 projects from the toe of the iron with an upturned extremity 22 arranged to terminate in front of said air jet member 7 with its extremity exposed in the path of the air discharged from the latter, and preferably substantially at right angles thereto. 75 80 85

A means for breaking the siphon to discontinue the flow of water therethrough is provided. This breaking means comprises an air port 23 formed in the wall of said rising leg 19 adjacent to the elbow of the siphon, through which, when open, air may enter the siphon passage to interrupt and prevent the rise of water through said rising leg. A ball valve 24 cooperates with said air 90 95 port 23, the same being disposed in a housing chamber 25, the latter being also provided with an air intake port 26 leading into the interior of the same.

If desired the water reservoir 17 may be 100 provided with an automatic means for maintaining a supply of water within the same, similar to that shown and described in my copending application for Letters Patent Ser. No. 68,561, filed November 12th, 1925. 105 Said means preferably comprises forming said reservoir 17 in the form of a relatively thin metallic shell, the bottom 27 of which is more or less resilient and yieldable to downward pressure. Fixed on the top of said iron 110

body is a water delivery member 28 provided with an intake duct or passage 29, which terminates at its inner end in an intake valve housing 30, from the lower side of which extends a valve passage 31 into communication with the interior of said water reservoir 17. Surrounding the upper end of said valve passage 31 is a valve seat 32. Secured to the resilient bottom 27 of said reservoir is an upwardly extending valve stem 33, to the upper free end of which is attached a valve member 34 for cooperation with said valve seat 32. The upper end of the valve housing 30 may be provided with a detachable cap 35, and, if desired, a pull-spring 36 may be connected between said cap 35 and valve member 34 to assist the opening movement of the latter. Suitably coupled with the outer end of said water delivery member 28, in communication with the duct or passage 29, is a flexible water feed conduit or pipe 37 leading from a suitable source of water supply.

The operation of the iron is as follows:—

Water is supplied through the feed conduit or pipe 37. If the reservoir 17 is empty, the bottom 27 thereof will be disposed in normal initial raised position, and consequently the stem 33 of the valve 34 will be moved upward to unseat the latter and thus open the valve passage 31 to the flow of water from said feed conduit or pipe 37 into the interior of the reservoir 17. As the reservoir fills, the weight of the water upon the resilient bottom 27 thereof will tend to depress the latter, thus drawing downward the stem 33 until the valve member 34 seats itself and closes the valve passage 31 against further entrance of water. As the water is drawn out of the reservoir 17, when using the iron, and the initial weight of water is thereby reduced, the bottom 27 will tend to resume normal initial raised position, thus again unseating the valve member 34 for renewed entrance of water into the reservoir to compensate for the losses of use. As will be evident the action of the water admission valve 34 is thus automatic, and intermittent opening and closing of the same will automatically maintain an adequate supply of water within the reservoir 17 ready for use.

The water reservoir being filled, the iron is heated, whereupon the same is ready for use. If, as the pressing operation is carried out, the operator desires to dampen the goods, the air control valve is actuated by a proper manipulation of the lever 14, so that air, from a suitable source of supply under pressure, is caused to pass through the air pipe 6, and jet member 7 so as to be discharged from the latter. The blast of air thus produced sweeps past the discharge extremity 22 of the siphon 18, thus creating a suction within the latter, which is effec-

tive both to move the ball valve 24 into closed relation to the air port 23 of said siphon and to thereupon cause water from said reservoir 17 to ascend the rising siphon leg 19 and thence through the descending leg 20 for emission from the discharge extremity 22 of the siphon. The force of the air stream tends to shatter or atomize the emitted water, and since the direction of the air stream is in a downwardly and forwardly inclined path in advance of the toe of the iron, it follows that the water will be lightly deposited on the goods in the form of a fine spray in advance of the onward movement of the iron. The water thus deposited on the goods will dampen the same, so that as the hot iron advances over the thus dampened goods, the heat will evaporate the water and the moisture will assist the rapid and efficient smoothing out of the goods by the iron, in the manner well understood by those skilled in the art.

When it is desired to discontinue service of water spray to the goods, the operator simply releases the lever 14 of the air control valve thus discontinuing the discharge of air from the jet 7. The discharge of the air being thus discontinued, the suction effect thereof on the discharge end of the siphon stops and consequently the ball valve 24 is permitted to fall away from the air port 23 of the siphon, whereby the entrance of air into the rising leg 19 of the latter breaks the siphonic action, and delivery of water ceases. If desired the toe portion of the iron may be provided, at a point beneath the discharge extremity of the siphon with a suitably formed catch-basin 38, which serves to catch and hold away from the goods any drip from the siphon, which might occur upon discontinuance of its siphonic action.

I am aware that some changes may be made in the general arrangements and combinations of the various devices and parts, as well as in the details of the construction of the same, and I therefore reserve the right to such construction as do not depart from the scope of this invention as defined in the appended claims.

I claim:—

1. The combination with a sad iron of a water reservoir carried thereby, water discharge means communicating with said reservoir, and an air jet means coacting with said water discharge means for discharging an atomized mixture of air and water exteriorly of said iron.

2. The combination with a sad iron of a water reservoir carried thereby, a water delivery siphon leading from said reservoir with its discharge extremity exteriorly disposed at the toe of the iron, and a valve controlled compressed air delivery means having a jet positioned to discharge an air

stream across the discharge extremity of said siphon.

3. The combination with a sad iron of a water reservoir carried thereby, a water supply pipe leading to said reservoir, automatic means for controlling the flow of water from said supply pipe into said reservoir, a water discharge means leading out of said reservoir, and an air jet means co-acting with said water discharge means for discharging an atomized mixture of air and water exteriorly of said iron.

4. The combination with a sad iron of a water reservoir carried thereby, a water supply pipe leading to said reservoir, automatic means for controlling the flow of water from said supply pipe into said reservoir, a water delivery siphon leading from said reservoir with its discharge extremity exteriorly disposed at the toe of the iron, and a valve controlled compressed air delivery means having a jet positioned to discharge an air stream across the discharge extremity of said siphon.

5. The combination with a sad iron of a water reservoir carried thereby, a water delivery siphon leading from said reservoir with its discharge extremity exteriorly disposed at the toe of the iron, the ascending leg of said siphon having an opening, a normally unseated valve for closing said opening, and a valve controlled compressed air delivery means, the discharge ends of said siphon and air delivery means being adjacently arranged to discharge an atomized mixture of air and water exteriorly and in advance of the iron.

6. The combination with a sad iron of a water reservoir carried thereby, a water delivery siphon leading from said reservoir with its discharge extremity exteriorly disposed at the toe of the iron, the ascending leg of said siphon having an opening, a normally unseated valve for closing said opening, a valve controlled compressed air delivery means, the discharge ends of said siphon and air delivery means being adjacently arranged to discharge an atomized

mixture of air and water exteriorly and in advance of the iron, and a catch-basin portion provided in connection with the toe of said iron and disposed beneath the discharge extremity of said siphon to catch the drip from the latter when siphonic action is discontinued.

7. The combination with a sad iron of a water reservoir carried thereby, a water supply pipe leading to said reservoir, automatic means for controlling the flow of water from said supply pipe into said reservoir, a water delivery siphon leading from said reservoir with its discharge extremity exteriorly disposed at the toe of the iron, the ascending leg of said siphon having an opening, a normally unseated valve for closing said opening, and a valve controlled compressed air delivery means, the discharge ends of said siphon and air delivery means being adjacently arranged to discharge an atomized mixture of air and water exteriorly and in advance of the iron.

8. The combination with a sad iron of a water reservoir carried thereby, a water supply pipe leading to said reservoir, automatic means for controlling the flow of water from said supply pipe into said reservoir, a water delivery siphon leading from said reservoir with its discharge extremity exteriorly disposed at the toe of the iron, the ascending leg of said siphon having an opening, a normally unseated valve for closing said opening, a valve controlled compressed air delivery means, the discharge ends of said siphon and air delivery means being adjacently arranged to discharge an atomized mixture of air and water exteriorly and in advance of the iron, and a catch-basin portion provided in connection with the toe of said iron and disposed beneath the discharge extremity of said siphon to catch the drip from the latter when siphonic action is discontinued.

In testimony, that I, claim the invention set forth above I have hereunto set my hand this 25th day of January, 1926.

CHARLES A. BREWER.
